(57) **CLAIM**

The ornamental design for a spacer, as shown and described.

DESCRIPTION

FIG. 1 is a front perspective view of the spacer comprising the new design;

FIG. 2 is a back perspective view of the design of FIG. 1;

FIG. 3 is a top view of the design of FIG. 1;

FIG. 4 is a bottom view of the design of FIG. 1;

FIG. 5 is a left side elevational view of the design of FIG. 1, wherein the right side elevational view is a mirror image thereof;

FIG. 6 is a front elevational view of the design of FIG. 1; and

FIG. 7 is a back elevational view of the design of FIG. 1.

FIG. 8 is a front perspective view of an alternative embodiment of the spacer of FIG. 1;

FIG. 9 is a back perspective view of the design of FIG. 8;

FIG. 10 is a top view of the design of FIG. 8;

FIG. 11 is a bottom view of the design of FIG. 8;

FIG. 12 is a left side elevational view of the design of FIG. 8, wherein the right side elevational view is a mirror image thereof;

FIG. 13 is a front side elevational view of the design of FIG. 8; and,

FIG. 14 is a back side elevational view of the design of FIG. 8.

The broken lines shown in the figures are directed to the environment and are for illustrative purposes only and form no part of the claimed spacer invention.

The relatively light uneven broken lines shown in the figures represent contour, not surface decoration.
